UNITED STATES PATENT OFFICE.

CHARLES C. WIENTGE, OF PROVIDENCE, RHODE ISLAND, ASSIGNOR TO THE HOWARD & LOW COMPANY, OF SAME PLACE.

DESIGN FOR A SPOON, &c.

SPECIFICATION forming part of Design No. 20,947, dated July 14, 1891.

Application filed May 9, 1891. Serial No. 392,228. Term of patent 14 years.

To all whom it may concern:

Be it known that I, CHARLES C. WIENTGE, of Providence, in the county of Providence and State of Rhode Island, have originated and produced a new Design for the Shanks and Handles of Spoons and Like Articles, of which the following is a specification.

My design consists of a spoon-handle having the head of an Indian delineated upon it. The stem is appropriately embellished by representations of Indian corn.

The accompanying drawing is a front view of a spoon embodying my design.

It will be seen that the shank a of the spoon is ribbed near its junction with the bowl. This rib may represent a stalk of Indian corn. Farther from the bowl the shank is embellished by representations of ears a' of corn and leaves a^2 . The handle a^3 of the spoon is

ornamented with a delineation of the head of an Indian.

What I claim as my design, and desire to secure by Letters Patent, is—

The design for a spoon or like article, consisting of a shank having ribs representing stalks of corn, and said shank having at its upper portion the representation of ears of corn and leaves, and the handle having the head of an Indian delineated upon it, substantially as shown.

In testimony whereof I have signed my name to this specification in the presence of two subscribing witnesses.

CHARLES C. WIENTGE.
